CLAIM

The ornamental design for an instrument panel, as shown and described.

DESCRIPTION

FIG. 1 is a front view of an instrument panel showing the claimed design;

FIG. 2 is a left-side view of the instrument panel;

FIG. 3 is a right-side view of the instrument panel;

FIG. 4 is a top view of the instrument panel;

FIG. 5 is a rear view of the instrument panel;

FIG. 6 is a front left corner perspective view of the instrument panel;

FIG. 7 is a front right corner perspective view of the instrument panel;

FIG. 8 is a rear left corner perspective view of the instrument panel; and,

FIG. 9 is a rear right corner perspective view of the instrument panel.

The broken lines depict portions of the instrument panel that form no part of the claimed design.

1 Claim, 9 Drawing Sheets
